ATTORNEY.

UNITED STATES PATENT OFFICE.

ROBERT GOLDE, OF BROOKLYN, NEW YORK, ASSIGNOR TO THE ROYAL METAL MANUFACTURING COMPANY, OF NEW YORK.

DESIGN FOR A PICTURE-FRAME.

SPECIFICATION forming part of Design No. 23,183, dated April 10, 1894.

Application filed February 13, 1894. Serial No. 499,996. Term of patent 3½ years.

To all whom it may concern:

Be it known that I, ROBERT GOLDE, a subject of the Emperor of Germany, residing at Brooklyn, in the county of Kings, State of New York, have invented and produced a new and original Design for a Picture-Frame, of which the following is a specification, reference being had to the accompanying drawings, forming a part thereof.

10 The leading features of my design for a picture frame are the sides of the same of the representations of scrolls and flowers; next a group of scrolls and flowers forming a peak at top; next converging groups of scrolls and flowers forming corners at bottom; next the representation of a frill around the inner border of the frame, and finally a group of flowers, scrolls and lattice work.

15 In the drawing: A designates a picture frame, the sides of which are formed of representations of scrolls B and flowers C.

D designates lattice work which joins some of the scrolls and flowers, and E designates a shell which joins some of the scrolls B.

At the bottom of the frame two of the 25 groups form corners F, F', which converge at G, the corner F' consisting of scrolls B and flowers C, which diverge from the point II. The other corner F has in it the lattice work D, above referred to. At the top of the frame 30 there is a group of scrolls and flowers which form the peak J. K designates a frill around the inner border of the frame.

What I claim is—

The design for a picture frame substantially as shown and described.

ROBERT GOLDE.
